UNITED STATES PATENT OFFICE.

WESLEY J. BARRETT, OF MARION, NEW YORK.

BURIAL APPARATUS.

SPECIFICATION forming part of Letters Patent No. 760,773, dated May 24, 1904.

Application filed June 4, 1903. Serial No. 160,076. (No model.)

To all whom it may concern:

Be it known that I, WESLEY J. BARRETT, of Marion, in the county of Wayne and State of New York, have invented a new and useful Improvement in Burial Apparatus, which improvement is fully set forth in the following specification and shown in the accompanying drawings.

My invention is a lowering apparatus or an apparatus for suspending and lowering heavy bodies or weights, such as coffins, the mechanism of the apparatus being such that the rate of fall of the descending body is wholly under the control of the attendant even to entirely stopping its downward motion.

This apparatus is simple in construction and not costly to produce and is convenient and easily operated and controlled. It is adapted for various uses, as will be readily understood, being herewith shown as applied to the undertaker's use in the form of a burial apparatus for lowering caskets gently and easily into grave-openings.

The invention is hereinafter fully described, and more particularly pointed out in the claims, reference being had in this specification to the accompanying drawings, forming a part thereof.

Figure 1 is a plan view of the apparatus as in use at a burial, parts being broken away and the frame horizontally sectioned on the dotted line 1 1 in Fig. 6. Fig. 2 is a plan of the power-cylinder and associated parts, parts being broken away and the cylinder and other parts horizontally sectioned along the axis of the cylinder. Fig. 2½ shows the crank for rewinding the suspension-bands and bringing other parts of the device to their normal positions. Fig. 3 is a plan of the plunger and plunger-rod, parts being broken away and other parts horizontally and axially sectioned. Fig. 4 is an end view of the plunger seen as indicated by arrow in Fig. 3, the rod being in part broken away and transversely sectioned as on the dotted line at the point of the arrow. Fig. 5 is an end view of the plunger-rod seen in a direction opposite to that in which Fig. 4 is seen, showing the ball-bearing partly broken away. Fig. 6 is a vertical transverse section of the frame, taken on the

dotted line 6 6 in Fig. 1. Fig. 7 is an axial section of parts at the front end of the power-cylinder further showing the construction, parts being broken away. Fig. 8 is a view at the end of the frame seen as indicated by arrow 8 in Fig. 1, parts being broken away and the section being as on the dotted line 8' 8' in Fig. 2. Fig. 9 is a vertical transverse section of a part of the frame, taken as on the dotted line 9 in Fig. 1, parts being broken away. Fig. 10 is a transverse section of the plunger-rod and the adjacent end of the coacting winding-shaft, taken as on the dotted line 10 in Fig. 7. Fig. 11 is a side elevation of the joined ends of the sections of a suspension-band seen as indicated by arrow 11 in Fig. 1. Figs. 1, 2, 2½, 6, 8, and 9 are drawn to various scales smaller and Fig. 11 to a scale larger than that of Figs. 3, 4, 5, 7, and 10.

In the drawings, A, Figs. 1, 6, 8, and 9, is a hollow rectangular flat frame, preferably of wood, having a large rectangular opening O at the middle and holding in its hollow sides and ends the working parts of the apparatus. This frame when in use at a burial is placed horizontally upon the ground to surround or inclose the grave B, Fig. 1, the width of the opening O in the frame corresponding substantially with that of the grave. Within the hollow sides of the frame A are two parallel horizontal coacting shafts C D, Figs. 1, 2, 6, 9, and 10, resting in bearings b, rigid in the frame. These shafts are connected at one end of the frame by a crossed chain d, Figs. 1 and 6, running on sprockets a a on the respective shafts, so that both shafts must turn together and in opposite directions.

A pair of suspension-bands or suspenders f f, Figs. 1, 9, and 11, in joined sections for holding the casket or body E, have their inner ends secured to the shafts C D, respectively, in a manner to be wound thereon, as shown. These bands cross the opening O in the frame at right angles, emerging into the respective hollow sides of the frame through small horizontal openings c and in a manner connect the two shafts. The meeting ends of the sections of the bands under the middle of the body E are provided with metallic hoops or grips e e, which after the casket is down and the bands

slightly slackened will unlock or let go, so the detached sections may be again drawn up by a turning of the shafts C D. The bands *f* rest upon antifriction-rollers *g*, Figs. 1 and 9, held by hangers *h*, secured within the frame, the ends of the bands being secured to the respective shafts by some simple means, as clamps *i*.

In use for the purpose shown the suspending-bands *f* primarily reach across the grave B substantially horizontal with the casket resting thereon, as shown in Fig. 1, the inner ends of the bands being wound in rolls upon the respective shafts C D, the weight of the casket serving to turn the two shafts inward, unrolling the bands therefrom as the casket descends to the bottom of the excavation. To regulate the descent of the casket or body, I employ a checking-cylinder F, Figs. 1, 2, and 8, in the frame coaxial with the shaft C, having heads *k l* and filled with a suitable liquid, as oil.

G, Figs. 2, 3, and 4, is a plunger within the cylinder having an axial rod H threaded through the head *k*, Fig. 7, with its forward end entering the adjacent end of the shaft C, Figs. 1, 2, 7, and 10, which is hollow, as shown.

I is a side pipe connected with the two heads of the cylinder and forming a continuous passage for the oil from either end of the cylinder to the other, so that as the plunger is moved one way or the other longitudinally within the cylinder the oil may flow forward or backward to correspond. The outer end of the plunger-rod H is formed with a longitudinal groove or race *m* and the adjacent part of the hollow shaft C with an inturned spline or feather *n* to occupy and traverse the race *m* as the rod moves longitudinally in the shaft.

Now it will be understood that though the plunger-rod H may move longitudinally within the shaft C both must turn together, and when the shaft is turned by the weight of the body E, as stated, the rod will also turn and on account of its threaded bearing in the head *k* cause the plunger G to travel in the cylinder. Normally, to illustrate, the plunger stands at the rear end of the cylinder, as appears in Fig. 2, and when the rod H is turned by the revolving shaft toward the left the plunger will be drawn forward, forcing the oil in front of it through the side pipe I in the direction indicated by the arrow *o*, and, it will be understood, the plunger can move no faster than it is able to displace the oil, the latter escaping through the pipe I, as stated. A stop-valve K of ordinary kind and construction, Figs. 2 and 8, is inserted in the pipe I, through which the oil must pass, a hand-wheel L, Figs. 1 and 2, without the frame enabling the attendant to regulate the opening through the valve, and so the rate at which the oil may pass through it, and accordingly control at will the rate of the descent of the

casket into the grave. By wholly closing the passage through the valve the casket may be stopped in its descent.

To rewind the suspending-bands *f* onto the shafts C D and return the plunger to its normal position at the rear end of the cylinder, a crank N, Fig. 2½, is employed in connection with an enlarged part *p*, Figs. 1 and 6, rigid with the shaft C. The crank is formed with a square part *r*, and the part *p* is made with a corresponding square longitudinal socket *s* to receive the part *r*, as shown by dotted lines in Fig. 1, by means of which and the chain *d* both shafts and the rod H may be turned in a direction opposite to that in which they were turned by the weight of the casket, as stated. The part *r* of the crank is inserted through an opening (not shown) in the outer part of the frame A opposite the socket *s*, and when the shaft C is being turned by the crank and the plunger G moves backward the oil in the rear end of the cylinder flows into the front end of the cylinder through the pipe I, as indicated by dotted arrows in Figs. 2 and 7.

The front head *k* of the cylinder F is formed with a lengthened axial part *t*, Figs. 2 and 7, extending inwardly in the cylinder and threaded at its free end, upon which is mounted an internally-threaded packing-box *u*, inclosing a body of packing material *v* around the threaded rod H, as shown, to prevent the escaping of the oil along the rod. Also to cause the parts within the cylinder to act with minimum friction I provide a ball-bearing between the plunger G and the inner end of the plunger-rod H. (Shown in Figs. 3 and 5.) The rod H is fitted to turn freely in the frame *w* of the plunger, and is reduced at *a'* to receive upon it a cup *x* to hold bearing-balls *y*. An outer part or cap *z* is threaded onto the part *a'* to complete the enclosure for the balls, the cap *z* being rigid with the rod H, while the latter turns freely in the cup *x*. By means of this provision and the construction of the parts the rod H is permitted to turn freely in the plunger, the latter not revolving, but merely sliding longitudinally in the cylinder when the device is operating.

The plunger is preferably constructed, as shown, with a free metal ring *b'*, Fig. 3, and two fibrous rings *c'*, encircling an imperforate hollow head *d'*, upon the open end of which head the frame *w* is threaded to hold the parts together.

What I claim as my invention, and desire to secure by Letters Patent, is—

1. A lowering apparatus comprising a pair of shafts arranged parallel with each other, suspenders for holding the weight to be lowered wound upon and connecting the shafts, means for causing the shafts to turn simultaneously in opposite directions, a cylinder for holding liquid, a plunger in said cylinder, means connecting the plunger with one of the

shafts, a side pipe outside of the cylinder and connecting the opposite ends thereof, a valve in said pipe, and a ball-bearing between the plunger and its rod.

5 2. An apparatus such as described having a pair of hollow coating rotatory shafts, divided suspenders for holding the body to be lowered wound upon and connecting the two shafts, a cylinder coaxial with one of said shafts having heads for holding a liquid, a plunger in the cylinder, an axial rod threaded through a head of the cylinder and telescopically connecting the plunger with said coaxial shaft, said rod being formed with a grooved end to enter the shaft, and a feather in the shaft to occupy the groove and a ball-bearing between the plunger and the plunger-rod.

3. A lowering apparatus comprising a pair of parallel shafts, suspenders for holding the weight to be lowered wound upon and connecting said shafts, means for causing the shafts to turn simultaneously in opposite directions, a cylinder coaxial with one shaft of

the pair and having heads for holding liquid, one head having an axial internally-threaded part extending within the cylinder, a packing-box for the rod at the end of said inwardly-extending part, a plunger, a threaded rod telescopically connected with the plunger and engaging the threads of said internally-extended part of the head, the outer end of said rod having a longitudinal groove, said groove being engaged by a spline carried by the said coaxial shaft the plunger having a frame in which the plunger-rod freely turns, said rod being reduced, a cup on said reduced part, balls in said cup, and an outer part threaded on said reduced part and rigid with the rod.

In witness whereof I have hereunto set my hand, this 27th day of May, 1903, in the presence of two subscribing witnesses.

WESLEY J. BARRETT.
